UNITED STATES PATENT OFFICE.

JOHN RING, OF ST. LOUIS, MISSOURI, ASSIGNOR OF FOUR-FIFTHS TO JAMES J. McLOUGHLIN AND BROWNLEE W. TAYLOR, BOTH OF NEW ORLEANS, LOUISIANA.

PASSENGER-FARE COLLECTOR.

SPECIFICATION forming part of Letters Patent No. 437,622, dated September 30, 1890.

Application filed January 28, 1890. Serial No. 338,347. (No model.)

To all whom it may concern:

Be it known that I, JOHN RING, of the city of St. Louis, in the State of Missouri, have invented a certain new and useful Improvement in Passenger-Fare Collectors, of which the following is a full, clear, and exact description, reference being had to the accompanying drawings, forming part of this specification.

This is a device which is for that class of fare-collectors which are carried by the conductor and into which the fare is dropped on receiving the same from the passenger.

The improvement includes a number of plates jointed together and so constructed and arranged that they close the passage by which the tickets or coin enter the receptacle, and so that when the passage is closed at one place it is opened at another, as will be fully described. The improvement also includes a mouth formed with projections to interfere with the insertion of an instrument for extraction of the fares and the extraction of any fares engaged by such instrument.

The points of novelty are set forth in the claims.

Figure I is a perspective view of the part of the fare-collector to which my invention is applied with part broken out. Fig. II is a vertical section. Fig. III is a transverse section at III, III, Fig. II.

1 is the case, having a receiving-mouth 2. This mouth is formed with projections 2^a 2^b to interfere with the insertion of an instrument for extraction of the fares and the extraction of any fares engaged by the instrument.

3 is a pane of glass in the side of the case, through which the ticket or coin may be examined.

4 is a swinging upper plate extending across the whole width of the passage 5, but having free movement therein on a fixed pivot 6 at its upper end.

7 is a spring secured to the plate 4 or to the case and acting to force the plate into the position shown in Fig. II, so as to close the passage and hold the fare in position for examination through the glass 3.

8 is a finger projecting from the lower edge

of the plate 4 through a curved slot 9 in the side of the case 1, and having a thumb-knob 10, by pressure against which the plate 4 may be moved into the vertical position indicated by dotted lines in Fig. II.

11 is a connecting upper plate or rod hinged at 12 to the bottom edge of the plate 4 and hinged at 13 to the upper edge of a sliding vertical plate or rod 14, which is in turn hinged at the lower edge 15 to a connecting lower plate 16. The pintles 12 and 13 work in vertical guides 17, so as to hold the plate 14 in a vertical position—that is to say, parallel with the sides of the case A. The plate 16 is hinged at 18 to the upper edge of a swinging lower plate 19, whose lower edge is hinged at 20 to the side of the case. The construction is such that the plates 16 and 19 are moved out into the position shown by dotted lines in Fig. II, when the plates 4 and 11 are moved into the position shown in dotted lines in the same figure. In this case the fare is released from the plate 4 and falls upon the plate 16, and when the thumb-knob is released from pressure the spring 7 throws the plates into the position shown by full lines in Fig. II, and the fare drops from the plate 16 into the receptacle 21, which may be a bag having a neck 22 that slips on the lower end 23 of the case 1, and may be secured by a hasp 24 and a padlock on the staple 25.

26 is a spring behind the plate 19, tending to throw it outward when the plate 4 is thrown inward. The spring 7, however, has greater strength than the spring 26, so that the parts are held in the normal position shown in full lines in Fig. II, except when pressure is brought upon the thumb-knob.

27 is a projection below the plate 19, against which the fare impinges in descending, and which prevents the escape of the fare or the introduction of an instrument for removal of the fares from the receptacle 21. 28 is a pivoted plate which closes the passage at that point in case the instrument is turned mouth downward, and thus prevents the escape of the fares.

I claim as my invention—

1. The combination of the case 1, having a

receiving-mouth 2, the swinging upper plate 4, hinged at its upper end and adapted to be placed in an inclined or vertical position, the connecting upper plate 11, hinged to the bottom edge of the swinging upper plate and adapted to be placed in an inclined or vertical position, the sliding vertical plate 14, hinged to the lower edge of the connecting upper plate, the connecting lower plate 16, hinged to the lower edge of the sliding vertical plate and adapted to be placed in a vertical or inclined position, and the swinging lower plate 19, hinged to the bottom edge of the connecting lower plate at its upper end, hinged at its lower end and adapted to be placed in a vertical or inclined position, substantially as described.

2. The combination of the case 1, having a transverse slot 9 and a receiving-mouth 2, the pane 3, the swinging upper plate 4, having a finger 8 projecting through the slot, connecting upper plate 11, vertical sliding plate 14, connecting lower plate 16, and the swinging lower plate 19, substantially as described.

3. The combination of the case 1, having a receiving-mouth 2, the pane 3, the projection 27, and the hinged plate 28, the swinging upper plate 4, having a finger 8, connecting

upper plate 11, vertical sliding plate 14, connecting lower plate 16, and the swinging lower plate 19, substantially as described.

4. The combination of the case 1, constructed with a receiving-mouth 2, having projections 2^a 2^b, the pane 3, the projection 27, and the hinged plate 28, the swinging upper plate 4, having a finger 8, connecting upper plate 11, vertical sliding plate 14, connecting lower plate 16, and the swinging lower plate 19, substantially as described.

5. The combination, in a portable fare-collector, of the hinged plates 4 16, connected together and to the case by connections 11, 14, and 19, spring 7, finger 8, and projections 2^a 2^b at the mouth, substantially as shown.

6. The combination, in a portable fare-collector, of the mouth provided with angular projections 2^a 2^b, the hinged plates 4 16, the connections 11 14 19, the spring 7, the finger 8, the projection 27, and the hinged plate 28, all constructed and arranged substantially as shown and described.

JOHN RING.
